UNITED STATES PATENT OFFICE.

HENRY H. VAUGHAN, OF CHICAGO, ILLINOIS, ASSIGNOR TO RIDGELY AND JOHNSON TOOL COMPANY, A CORPORATION OF ILLINOIS.

THROTTLE-VALVE.

SPECIFICATION forming part of Letters Patent No. 718,550, dated January 13, 1903.

Application filed March 19, 1901. Serial No. 51,829. (No model.)

To all whom it may concern:

Be it known that I, HENRY H. VAUGHAN, a citizen of the United States, residing at Chicago, in the county of Cook, State of Illinois, have invented certain new and useful Improvements in Throttle-Valves; and I hereby declare the following to be a full, clear, and exact description of the same, reference being had to the accompanying drawings, where-

in—

Figure 1 is an end elevation, and Fig. 2 an axial section, of a throttle-valve embodying my invention.

Like symbols refer to like parts wherever they occur.

My invention relates to the construction of throttle-valves in general, but has been especially devised for use with pneumatic or motive-fluid operated tools—as, for instance, pneumatic drills—where a compact-trigger or quick-opening valve is desired. The objections existing to this class of throttle-valves as heretofore constructed have been due in some instances to the arrangement and movement of the valve at right angles to the center line of the motive-fluid-induction pipe, which necessitated the use of stuffing-boxes to obtain tight joints and resulted in obstructions which inconvenienced the workman and limited the utility of the devices, while in other instances where an axial arrangement of the valve has been attempted the air-passages have been so obstructed as to materially interrupt and retard the free and effective flow of the motive fluid.

The object of the present invention is not only to avoid objectionable obstruction on but in the throttle-valve, to materially simplify the construction of this class of valves, and insure a free and unobstructed flow of the motive fluid in and through the valve and supply-pipe.

To this end the main feature of my invention resides in the combination, with a tubular outer shell or casing having an axially-supported stem-guide, of an included perforated tubular chamber into which the axially-supported stem-guide projects and a piston-valve within said tubular valve-chamber and arranged to be actuated by the axially-sup-

ported stem, whereby a plurality of concentric and communicating annular chambers are formed within the valve and practically one-half of the area of the pipe or casing is utilized for the free flow of the motive fluid.

There are other minor features of invention, all as will hereinafter appear.

I will now proceed to describe my invention more fully, so that others skilled in the art to which it appertains may apply the same.

In the drawings, 1 indicates the outer shell or casing, which is or may be of tubular form and threaded at one end, as at 1^a, for connection with the motive-fluid-supply pipe and at the other end, as at 1^b, for connection with the pipe leading to the machine or tool to be operated.

Adjacent to the delivery end of the casing 1 said casing is indented or provided with a lever-pocket 2 for the reception of the short arm of an elbow-lever L, pivoted on the casing, as at m, the long arm of which lever extends parallel or substantially parallel with the casing 1 and is utilized to operate the throttle-valve. Projecting axially within said casing 1, supported from and communicating with lever-pocket 2, is a tubular stem-guide 3, within which is movably arranged a stem 4, one end of which extends into the lever-pocket 2, in contact with the lever-arm there-in, and the other end of which extends into an axially-arranged valve-shell or valve-chamber and is in contact with a piston-valve longitudinally movable in said valve-chamber.

5 indicates a tubular valve-chamber whose external diameter is so much less than the internal diameter of the shell or casing 1 as to insure an annular chamber between the two, which may have an area practically equal to about half the area of the containing casing or pipe 1. This valve-chamber is closed at one end, the other or open end being screw-threaded to engage the screw-threads 1^b on that end of the casing or shell 1, and thus be detachably supported longitudinally within the casing 1 and around the centrally-located stem-guide 3.

The valve-chamber 5 is provided with a series of perforations or ports 5^a, which are

closed by means of a longitudinally-movable piston-valve 6, said piston-valve being perforated longitudinally, as indicated in dotted line, Fig. 2, to balance the same and being 5 normally supported by a spring 7 in such position as to close the ports 5^a, but may be moved longitudinally of its case by the stem 4 when actuated by the lever L to unclose the ports 5^a and permit the flow of the motive 10 fluid.

The construction being substantially such as hereinbefore pointed out, the operation of the devices will be as follows: The long arm of the lever L being depressed, its short arm 15 will impart an endwise movement to the stem 4 within the stem-guide 3, which acting axially on the piston-valve 6 will cause it to move longitudinally in the valve-shell 5, thus compressing the spring 7 and uncovering the 20 ports 5^a, which allows the free and unobstructed flow of the motive fluid through the annular chamber surrounding the axially-positioned stem-guide 3, out of ports 5^a into and 25 through the annular chamber surrounding the valve-chamber, and thence to the point of its utilization.

Among the advantages of my invention are the increased area of the pipe or casing reserved for the free flow of the motive fluid, 30 the extreme simplicity of the combining casing, valve-chamber, and valve, and the facility with which the device can be dismembered for cleaning or repairing the same.

Having thus described my invention, what 35 I claim, and desire to secure by Letters Patent, is—

1. In a throttle-valve, the combination with a tubular casing or shell provided with a lever-pocket which extends into said shell and 40 having a stem-guide connected with said lever-pocket, of a valve-chamber arranged longitudinally within said shell and inclosing said stem-guide, a stem, and a piston-valve

within the valve-chamber; substantially as and for the purposes specified. 45

2. In a throttle-valve, the combination with a tubular casing having a lever-pocket and a stem-guide connected therewith and located centrally of the casing, of a stem endwise movable in the stem-guide, a lever pivoted on the 50 casing for actuating said stem, a valve-chamber arranged within the casing and inclosing the stem-guide, and a spring-supported piston-valve within the valve-chamber and in line with the stem, substantially as and for 55 the purposes specified.

3. In a throttle-valve, the combination with a casing having a lever-pocket and a stem-guide arranged axially of the casing and supported from the lever-pocket, of a tubular perforated valve-chamber detachably supported within the casing and which incloses the stem-guide, a stem, a piston-valve within the valve-chamber, and a lever for actuating the stem, substantially as and for the purposes specified. 65

4. In a throttle-valve, the combination with a tubular casing having an axially-supported stem-guide, of a tubular valve-chamber arranged longitudinally within the tubular casing and inclosing the axially-placed stem-guide whereby concentric and communicating annular chambers are formed within the valve, a suitable piston-valve within the tubular valve-chamber, a stem movable endwise in the stem-guide, and means for actuating said stem and piston-valve, substantially as and for the purposes specified. 75

In testimony whereof I affix my signature, in presence of two witnesses, this 15th day of 80 March, 1901.

HENRY H. VAUGHAN.
